UNITED STATES PATENT OFFICE.

FRANK G. BREYER, OF BRONXVILLE, NEW YORK, ASSIGNOR OF ONE-HALF TO J. A. SINGMASTER, OF NEW YORK, N. Y.

METHOD AND APPARATUS FOR UTILIZING AND BURNING ANTHRACITE DUST COAL AND THE LIKE.

Application filed June 6, 1927. Serial No. 198,719.

This invention relates to the combustion of finely divided combustible material for heating and steam generating purposes and for the generation of gas, and is particularly applicable to the economical burning and utilization of fine anthracite dust or "dirt" coal for these indicated purposes.

Up to the present time the burning of such fine anthracite dust or dirt coal for power purposes and for generating gas has not been successful. It cannot be economically burned on grates, either stationary or mechanical, because it is impossible to get a sufficient volume of air through the bed for economical combustion without blowing holes through the bed, through which the air rushes, leaving adjacent areas of fuel unburned. The coal is so fine and the interstitial spaces are so small as to set up a frictional resistance which simply does not permit the even flow of the requisite volume of air through the bed on the grate. Nor can anthracite dust or "dirt" be economically burned in pulverized coal burning equipment. This is largely because anthracite coal burns slowly if the coal particles are of any size, while on the other hand if the anthracite is crushed very fine, much finer than bituminous coal has to be crushed to burn in pulverized coal burning equipment, it will burn satisfactorily but the cost of such crushing is excessive. Moreover the bulk of the anthracite fine coal now available on the dumps and currently produced, has such a high ash content, very much higher than bituminous coal for similar purposes, that it must first be mechanically concentrated, floated, or the like to rid it of the larger portion of the ash forming constituents, slate, clay, etc. before it can be used for firing in powdered form. Concentrating as ordinarily practiced on anthracite dust coal adds not only to the cost of preparation, but results in considerable losses of combustible matter carried off with the ash. In addition the anthracite flame is short and is so very hot, that it is difficult of control and excessively scorifying on the brick work of the combustion chambers.

It has been proposed to briquet fine anthracite coal and burn it under boilers but the cost of briquetting and utilization according to prior practice has more than out-

balanced the difference in cost between dust coal and the coarser steam sizes such as #1, 55 2, 3 buckwheat coals which can be successfully burned on traveling grate types of stokers. In the practice of briquetting fine fuel for use in boiler and gas furnaces it has been assumed that the briquettes must be 60 made quite strong and capable of maintaining their form indefinitely, and accordingly elaborate and expensive briquetting methods have heretofore been employed, including the use of large quantities of binders and of special baking and curing operations. Moreover, much thought and expense have been involved in making such briquettes waterproof, inasmuch as a reserve supply of briquetted fuel had to be kept on hand, to take 70 care of possible breakdowns in the briquetting plant, and this large reserve supply had to be handled and stored.

According to my invention I entirely avoid the expensive and uneconomical crushing, 75 purifying, concentrating and briquetting operations heretofore practiced in the burning and utilization of fine anthracite dust or dirt coal in the generation of steam, and I effect this by feeding the natural untreated, unpurified and non-briquetted anthracite dust or dirt directly to the front end of the boiler furnace combustion chamber and upon the moving grate and in the form of agglomerates or compressed masses of loosely adhering particles of suitable shape and sufficient size to permit and facilitate the passage of an even and uniformly distributed blast of combustion supporting air and steam up through the agglomerated masses or compressed anthracite bed, the agglomerates being formed in continuous operation during the passage of the fuel dust to the furnace and the extreme fines contained in the anthracite dust being utilized to hold it together in the form of the agglomerates from the time they leave the agglomerating device until they are combusted. By simultaneously passing steam in suitable quantities with the blast of combustion supporting air through the bed of agglomerated anthracite dust to form combustion gases (CO and H) and by admitting thereabove air for supporting the combustion of the combustion gases, I am able to obtain a long bituminous-coal-like flame from the burning of the an-

thracite dust or dirt and in a particularly economical manner. The agglomerates being green when fed to the furnace, the combustion chamber forms a combined drying, 5 and combustion space therefor. The agglomerating device must be capable of receiving the green untreated anthracite dust or dirt and forming agglomerates thereof or masses of loosely adhering particles as by 10 mechanical compressing operations, and such device preferably also forms the regulating means for supplying the required quantity of coal dust to the furnace in accordance with the demands of the steam generation, 15 this latter function being obtained as for example by varying the speed of the agglomerating device.

For a better understanding of the invention, reference may be had to the accompanying drawings illustrating an apparatus 20 for practicing the same, wherein,—

Fig. 1 is a diagrammatic view partly in 25 sectional elevation illustrating the application of my invention to the generation of steam, Fig. 1^a is a diagrammatic front view of this apparatus with certain parts removed, and

Fig. 2 is a diagrammatic view partly in 30 section of an apparatus illustrating the application of my invention to the production of gas.

Referring to Fig. 1 of the drawing, I have indicated a steam boiler 1 disposed at one end of an elongated combustion chamber² 35 of a suitable boiler furnace having an arch roof indicated at 3 and an arch 4 at the end of the combustion chamber opposite the boiler 1. The side wall of the furnace is provided with openings 5 leading from the 40 outside into the combustion chamber 2 for a purpose hereinafter set forth. I have indicated diagrammatically a moving grate 6 passing from the front end of the combustion chamber 2 to and under the boiler 1, this grate being of any standard construction 45 and carried by drums indicated at 7. The grate 6 is adapted to receive and carry a bed of anthracite fuel 8 extending from the front end of the combustion chamber 2 to the rear end thereof underneath the 50 boiler 1, the top line of the bed of fuel being indicated by the broken line 8', and the bed being indicated as gradually decreasing in depth towards the rear end, a suitable 55 dump 9 being indicated for receiving the ash after the complete combustion of the anthracite by passing through the combustion chamber 2. I have indicated at 10 any suitable means for supplying the anthracite 60 dust or dirt coal 11, and at 12 I have indicated diagrammatically an agglomerating device or apparatus disposed between the feeding means 10 and the front end of the combustion chamber 2 of the furnace, the 65 device or apparatus 12 being capable of re-

ceiving the anthracite dust or dirt coal 11 and forming agglomerates thereof of suitable shape and sufficient size to form the required character and permanence of fuel bed 8 upon the grate 6. From the device or apparatus 12 the anthracite dust, which is now in the form of agglomerates or masses 13 of loosely adhering particles, is delivered to a laterally inclined belt-conveyor 14, the latter running along in front of the boiler 70 furnace and above the level of the grate 6 so as to permit the agglomerates 13 to be conveyed by gravity to the front end of the combustion chamber 2 underneath the arch 4 and upon the front end of the moving 75 grate 6. The conveyor 14 is indicated as laterally inclined downwardly toward the front end of the furnace so as to cause the agglomerated anthracite dust to readily slide off, and a gravity slide or chute 15 is 80 indicated for guiding the anthracite dust in the form of the agglomerates from the conveyor to the grate 6 underneath the arch 4. The slide or gravity chute 15 may be perforated for a portion of its length to permit 85 the passage therethrough of fines and agglomerated parts of unsuitable dimensions for the bed 8, which fall down through a chute 16 having a flaring opening or mouth immediately below the perforated part of 90 the gravity slide 15. The agglomerating device or apparatus 12 may be of any suitable character, but preferably consists of compression rollers of a shape and form to receive and form the anthracite dust into 95 the desired agglomerates by pressure operations, fines contained in the anthracite dust being utilized to hold and maintain the agglomerated material in the agglomerated form during the passage from the device 12 100 to and through the combustion chamber 2. The device or apparatus 12 is preferably also of a character to enable the quantity of fuel to be supplied to the boiler furnace to be varied at will or according to the demands of the boiler,—as for example by a 105 variation in speed of the rollers. The details of the device 12 are omitted for convenience in illustration. I have indicated in Fig. 1^a this device 12 as including a hopper 115 31 and a pair of rollers 32.

Underneath the moving grate 6 with the fuel bed 8 thereon, I have indicated a chamber 17, the bottom and end walls of which are indicated respectively by the numerals 120 18 and 19. Into this chamber leads a blast pipe or conduit 20 for the supply of a suitable blast of combustion supporting air, as for example a forced draft as generally employed in boiler furnaces. I have also indicated diagrammatically as leading into this blast conduit 20, a steam supply line 21, and by this arrangement a suitable quantity of steam may, if desired, be introduced into the blast of combustion supporting air en- 125 130

tering the chamber 17 and caused to pass therewith up through the grate 6 and the fuel bed 8 of anthracite dust agglomerates. By reason of the agglomerated character of the anthracite bed 8, the air and the steam are permitted to pass therethrough in a uniformly distributed manner throughout the length and breadth of the fuel bed 8 and to thereby effect complete combustion and utilization of the energy of the anthracite dust. The admission of the steam and passage of the same with the combusting air up through the anthracite fuel bed 8 produces the combustion gases CO and H, the combustion of which gases within the combustion chamber 2 is supported by air admitted through the side openings 5 above the fuel bed 8, and a long heating flame is thereby obtained from the anthracite fuel and in a particularly economical manner. The only treatment to which the anthracite dust or dirt 11 has been subjected in its passage to the front end of the combustion chamber 2 of the furnace is the agglomerating of the same in the passage through the apparatus 12. The necessity for briquetting with the attendant elaborate and expensive operations is entirely obviated, and in the preferred practice the anthracite dust is used as it comes from the mines without concentration or purification.

Ordinarily in practice the green anthracite dust agglomerates are passed from the conveyor 14 to the front end of the combustion chamber 2 underneath the furnace arch 4 without any intermediate drying or curing operation, and accordingly the front end of the combustion chamber 2 serves as a combined drying and combusting chamber. It is understood, however, that if desired, waste gases or other drying or heating means may be passed through the anthracite dust agglomerates as they pass down the gravity slide or chute 15, upon the grate to partially dry them before they reach the combustion chamber. It is also understood that suitable conveyors may be provided for conveying the fines, etc. dropping down the chute 16 back to the supply of anthracite dust or dirt coal. Ordinarily I prefer to form the agglomerates of the natural untreated anthracite dust and with the addition of no binder thereto, but it may be desirable in certain cases to add a small quantity of binder to the dust 11 to assist the fines contained therein in holding the fuel in the agglomerated form. Agglomerates as large as from three to six ounces formed without addition of a binder hold their form sufficiently while passing through the combustion chamber to maintain the desired character of bed 8, namely a bed through which a strong blast of air and steam may be evenly and uniformly diffused without the formation of blow holes, etc.

I have shown in Fig. 1 only one boiler and furnace of a bank of two or more, all of which may be fed by the same conveyor 14 disposed and running in front thereof.

In Fig. 2 I have indicated an apparatus 70 for the production of gas. In this case the furnace has an arch roof 25, an end wall 26 and front arch 27 and is otherwise entirely enclosed except for the outlet 28 for the gas or gases produced, the outlet 28 being near 75 the front end of the furnace. The apparatus otherwise is identical with the apparatus of Fig. 1 except that since the potential energy contained in the solid coal is to be converted to potential heat energy in the gases 80 CO and H, a larger quantity of steam must be admitted with the air, and accordingly the steam inlet 21' must be capable of delivering a sufficient quantity of steam for this purpose. The operation and function- 85 ing of the apparatus is substantially the same as described in connection with Fig. 1, the anthracite dust or dirt 11 being agglomerated by passing through the device or apparatus 12 and from there delivered in 90 the form of agglomerates to the moving grate 6 passing through the combustion chamber of the gas furnace. By agglomerating the anthracite dust 11 and introducing it directly upon the grate 6 into the form of 95 the moving bed 8, the air and steam admitted into the chamber 7 are permitted to be uniformly diffused throughout the bed 8 during their passage therethrough and the potential energy of the anthracite dust is 100 thereby economically converted into potential heat energy in the gases delivered through the outlet 28. A strong blast of air and steam may be forced through the bed 8 without the production of blow holes, 105 the resistance to passage therethrough being substantially uniform and even throughout the bed.

I claim:

1. The method of utilizing anthracite coal 110 dust and the like in steam boiler and gas producer furnaces of the traveling grate type comprising, in a continuous operation, compressing the dust into masses of loosely adhering particles, feeding the masses directly to the furnace and burning the same therein.

2. The method of utilizing anthracite coal 115 dust and the like in steam boiler and gas producer furnaces of the traveling grate type which comprises forming said dust into masses of loosely adhering particles by pressure, feeding the masses so formed directly into a furnace in continuous operation, and burning said masses therein.

3. The method of utilizing anthracite coal 120 dust and the like in steam boiler and gas producer furnaces of the traveling grate type which comprises in continuous operation compressing said coal dust into masses 130

of loosely adhering particles and of such size and shape that a bed of these masses is uniformly and amply porous to combustion gases, feeding the masses so formed directly from the compressing device into the furnace, and progressively passing a bed thereof through the furnace combustion chamber while passing a draft of combustion supporting air up through the progressively moving bed.

4. The method of utilizing anthracite coal dust and the like in steam boiler and gas producer furnaces of the traveling grate type comprising, in a continuous operation, compressing the dust into green masses of loosely adhering particles, feeding said masses directly from the compressing device to and through the combustion chamber of the furnace where they are first cured and then combusted and while the masses are moving through the combustion chamber, passing a forced draft of combustion supporting air evenly and uniformly through the bed.

5. The method of utilizing anthracite coal dust and the like in steam boiler and gas producer furnaces of the traveling grate

type which consists, in continuous operation, of compressing the dust into masses of loosely adhering particles, feeding the masses directly from the compressing device to a traveling grate furnace and progressively passing a bed thereof through the furnace combustion chamber and forcing a draft of air and steam up through the progressively moving bed of compressed masses and supplying air above the bed to support combustion of the gases formed.

6. The method of utilizing anthracite coal dust and the like in steam boiler and gas producer furnaces of the traveling grate type which comprises, in a continuous operation, compressing the fine fuel into masses of loosely adhering particles, passing these masses directly and continuously from the compressing means to and through the combustion chamber of the furnace and utilizing the compressing means to regulate the quantity of coal dust masses supplied to the furnace.

In testimony whereof, I have signed my name to this specification.
